UNITED STATES PATENT OFFICE

GILLES HOLST, OF EINDHOVEN, NETHERLANDS, ASSIGNOR, BY MESNE ASSIGNMENTS,
TO GENERAL ELECTRIC COMPANY, A CORPORATION OF NEW YORK

GAS FILLED DISCHARGE TUBE

Application filed January 22, 1927, Serial No. 162,900, and in the Netherlands January 29, 1926.

With enclosed arc discharges the heating of the anode is dependent on the nature of the gaseous filling, for if the latter consists of a non-rare gas such as nitrogen, the heating 5 of the anode is equal to the product of the current intensity and a voltage v which in the case of tungsten anodes is about 20 volts, whereas with arc discharges in a rare gas this voltage v only amounts to about 4½ 10 volts. It is evident that the latter case is more unfavourable than the former as in order to obtain the same heating effect a much greater current intensity is needed so that on that account the use of a filling of nitrogen 15 would be preferable. On the other hand, however, a gaseous filling consisting of one of the rare gases presents the advantage that the arc can be struck more easily. The invention has for its object to combine the two ad- 20 vantages by taking such measures that in the case of arc discharges in a rare gas the said voltage v can be raised to a value consider- ably higher than 4½ volts.

According to the invention, this purpose is 25 attained by arranging between the main electrodes one or more fixed auxiliary electrodes which are shaped so as to allow the discharge to pass, but which take a negative potential during this discharge.

30 In that case the auxiliary electrode may consist of an insulatedly arranged ring or of a ring which, being provided with a leading-in wire of its own, may be connected to the negative pole of the source of current.

35 The accompanying drawing represents diagrammatically two embodiments of the invention in which only those parts of the arc lamp are indicated by reference numerals which directly have relation to the invention.

40 In the drawing:

Figure 1 illustrates the case where the auxiliary electrode is arranged so as to be insulated and

45 Figure 2 represents the case in which the auxiliary electrode is provided with a leading-in wire of its own.

Between two spherical electrodes 1 and 2 which for example may be made of tungsten, is arranged an annular auxiliary electrode 3 50 of such diameter that it does not impede the

discharge between the electrodes 1 and 2. The main electrodes 1 and 2 as well as the auxiliary electrode 3 are sealed into the pinch of a glass foot 4. In the case illustrated in Figure 1 only the electrodes 1 and 2 are provided with leading-in wires. Whenever a discharge between the electrodes 1 and 2 is produced, no matter whether it is a direct current or an alternating current discharge, a negative potential will be impressed on the 55 ring 3 under the influence of the negative electrons produced in great numbers. Due to this negative potential the ring 3 exerts an attractive action on all positive ions that try to diffuse towards the anode. As, probably, 60 it is just these positive ions which in the case of an arc discharge in a rare gas reduce the said voltage v by partly neutralizing the negative space charge around the electrode which momentarily or continuously acts as 65 an anode, this voltage will be considerably increased owing to the presence of the ring 3. In accordance therewith it has been found that in neon this voltage can be raised to about 25 volts instead of to 4½ volts only, 70 when used without the auxiliary electrode 3. 75

It will be evident that it is not absolutely necessary that the auxiliary electrode 3 should have an annular shape, but also other shapes for example that of a frame may be used. It 80 is essential that the auxiliary electrode should allow the arc discharge to pass unhindered without itself taking part in it and that during this discharge, it should attract the diffusing positive ions.

It will also be clear that it is not necessary to arrange the ring 3 between the electrodes 1 and 2 so as to be insulated but that this ring may be provided with a leading-out wire of its own, said wire being connected in that case to a point having a negative potential, for example, to the negative pole of the source of current. An example thereof is illustrated in Figure 2 in which the negative pole is connected directly to the 85 ring 3 and through a steadyng resistance 5 to the cathode 2 of the discharge tube. It is obvious that this case can only be considered 90 when the tube is operated by a direct current.

What I claim is:

1. An electric arc discharge tube comprising a rare gas-filling, main cooperating electrodes and a ring-shaped auxiliary electrode for increasing the arc voltage, said ring-shaped electrode being mounted entirely between said main electrodes and surrounding the discharge path. 5
2. An electric discharge tube comprising a rare gas-filling, main cooperating electrodes and an auxiliary electrode for increasing the arc voltage, said auxiliary electrode being mounted entirely between said main electrodes and provided with a leading-in wire. 10
3. An electric device comprising a source of current and an arc discharge tube, containing a rare gas-filling, a main anode, a main cathode, and a fixed auxiliary electrode for increasing the arc voltage mounted entirely between said main electrodes and surrounding the arc discharge path, and provided with a leading-in wire, said leading-in wire being connected to the negative pole of said source of current, and an ohmic resistance connected between said negative pole 20 and said main cathode. 25
4. An electric arc discharge tube comprising a rare gas-filling, main cooperating substantially spherical electrodes and a fixed substantially annular auxiliary electrode for increasing the arc voltage, said auxiliary electrode being mounted entirely between said main electrodes and surrounding the arc discharge path and adapted to assume during the discharge a negative potential with respect to the electrode acting as an anode. 30
5. An electric arc discharge tube comprising a filling of neon, main cooperating substantially spherical tungsten electrodes and a fixed substantially annular auxiliary electrode for increasing the arc voltage, said auxiliary electrode being mounted entirely between said main electrodes and surrounding the arc discharge path and adapted to assume during the discharge a negative potential with respect to the electrode acting as an anode. 35
6. An electric arc discharge tube comprising a sealed envelope, a rare gas filling and main discharge electrodes in said envelope, in combination with an auxiliary electrode mounted entirely between said main electrodes and circumscribing the discharge path between said main electrodes while permitting a free discharge to be established under a higher voltage than exists as a direct discharge between said electrodes in the absence of the auxiliary electrode. 50
7. An electric arc discharge tube comprising a sealed envelope provided with a rare gas atmosphere and electrodes spaced apart therein, in combination with a conductive frame fixed within the envelope entirely between said electrodes and inclosing a cross-65 section of the discharge path between the

said electrodes for the purpose of segregating positive ions from said discharge path.

In testimony whereof I affix my signature, at the city of Eindhoven, this 28th day of December, 1926.
